UNITED STATES PATENT OFFICE.

JOHN T. COX, OF MOORESTOWN, NEW JERSEY.

TUMBLER-CLOSURE.

No. 866,436.

Specification of Letters Patent.

Patented Sept. 17, 1907.

Application filed February 17, 1903. Serial No. 143,750.

To all whom it may concern:

Be it known that I, JOHN T. COX, a citizen of the United States, and a resident of Moorestown, New Jersey, have invented certain Improvements in Tumbler-Closures, of which the following is a specification.

My invention relates to closures for vessels such as tumblers and jars, and consists of certain improvements in such closures which are designed for use with tumblers or jars having tapered walls.

10 The object of my invention is to make a simple and inexpensive cap which can be adjusted and firmly secured to tumblers or like vessels which vary slightly in size and shape, without relying on the use of yielding gaskets to accommodate such closure to vessels varying in size. This object I attain in the following manner, reference being had to the accompanying drawing, in which:

Figure 1, is a side elevation of a tumbler, showing my improved cap or closure in position; Fig. 2, is a plan view of the same; Fig. 3, is a sectional view; Fig. 4, is a perspective view of the closure securing means detached from the tumbler, and Fig. 5, is an enlarged sectional view of part of Fig. 3.

C is a tumbler or other vessel having inclined walls a tapering inwardly from top to bottom.

25 A is a cap of any suitable material, preferably coated on its underside with a water-proof substance, such as paraffin.

B is a band of thin metal having a wide flange b at its upper edge at right angles to its body and having its lower edge turned in to form a rib b', the edge of which is in engagement with the walls of the receptacle C is of less diameter than the upper portion of the band in engagement with the rim or edge of said receptacle. The

30 band B is split, having at one end a tongue d, and at the opposite end a slot or opening d' to receive said tongue. The band is of such width that it will take a secure hold on the tapered surface of the tumbler, as shown in Fig. 3, when clamped together by the engagement of the tongue with the slotted portion, and the final bending over of said tongue.

Tumblers employed as goods receptacles by manufacturers of preserves have to be carefully sorted at the present time, and all tumblers varying from a standard

45 diameter at the top are discarded as it is impossible to properly apply caps now in use to tumblers which vary from said standard. By the use of my invention, however, the tumblers need not be sorted, as the cap will accommodate itself to tumblers varying in diameter.

50 To apply the closure to the tumbler, the cap A is first

placed in position, then the band B is applied to the tumbler by opening it sufficiently to allow the top flange to rest upon the cap A; the lower inturned edge of said band being adjacent to the tapered walls of the tumbler. The two ends of the band are then forced towards each other, as indicated by the arrows Fig. 1; the tongue d is inserted in the slot or opening d' and enough circumferential or lateral pressure is applied to said band to insure the tight fit of the inturned rib b' against the tapered portion of the tumbler. This pressure will draw the band down and cause the flange b, which overlaps the cap A, to force said cap against the upper edge of the tumbler, then the tongue d is turned over and the closure is securely locked to the tumbler, and the edge of the inturned rib b' being of less diameter than the mouth of the tumbler, the rise of the closure is prevented, and the contents of the receptacle will be hermetically sealed.

In place of using a cap A of cardboard or other yielding material, a glass or metal cap may be used, and in this event a ring or lining of rubber or paper is to be employed to make a tight fit between the edge of the tumbler and the cap of glass or metal.

Having thus described my invention, I claim and desire to secure by Letters Patent:

1. A closure for open-mouthed vessels having inclined walls tapering inwardly from top to bottom, comprising a cap adapted to rest on the wall surrounding the mouth of said vessel, a vertical walled band having a portion engaging the edge of said cap to hold it against the mouth of the vessel, and provided with means for fastening said band, said band having an inturned lower edge initially formed therein for engagement with the outer wall of the vessel at a point below the mouth of the latter, the engaging edge of said band being of less diameter than the upper portion of the vessel.

2. The combination, with an open-mouthed vessel having inclined walls tapering inwardly from top to bottom, of a cap closing the mouth of said vessel and adapted to rest on top of the same, a split band having a horizontal flange to engage the cap, the body of the band being vertically walled at right angles to said flange and having an inturned lower edge initially formed therein adapted to engage the outer wall of the vessel at a point below its upper edge, the engaging edge of said band being of less diameter than the upper edge of the vessel and provided with means for adjustably securing said band to the vessel.

In testimony whereof, I have signed my name to this specification, in the presence of two subscribing witnesses.

JOHN T. COX.
